(57) **CLAIM**

The ornamental design for a moated animal food dish, as shown and described.

DESCRIPTION

FIG. 1 is a perspective view looking from the top of an embodiment of the moated animal food dish of the present invention, showing my new design;

FIG. 2 is a top plan view of FIG. 1;

FIG. 3 is a side elevational view of FIG. 1;

FIG. 4 is a bottom plan view of FIG. 1; and,

FIG. 5 is a cross-sectional view of FIG. 1.
